UNITED STATES PATENT OFFICE.

VINCENT LITCHFIELD RAVEN, OF DARLINGTON, ENGLAND.

RAILWAY SIGNALING APPARATUS.

No. 867,150.

Specification of Letters Patent.

Patented Sept. 24, 1907.

Application filed April 18, 1907. Serial No. 368,897.

To all whom it may concern:

Be it known that I, VINCENT LITCHFIELD RAVEN, a subject of the King of Great Britain and Ireland, residing at Darlington, in the county of Durham, England, have invented Improvements in Railway Signaling Apparatus, of which the following is a specification.

For enabling the driver of a locomotive engine to determine in foggy weather the position of the line signals designed to control the working of the line over which his engine or train is traveling, it has heretofore been proposed to provide on the track in advance of the line signal, a conducting bar which, when rubbed over by a pair of brushes carried by the engine, closes the circuit of an electric battery through an electric bell or other alarm on the engine and thereby bring such alarm into operation to indicate to the engine driver that he is approaching a signal, and for indicating when the line signal is in the safety attitude, it has been proposed to provide on the engine a separate bell or other alarm, and on the track, also in advance of the signal, either a movable bar, or a second stationary bar, for closing, when the engine runs over it, the circuit of a separate electric battery, that is under the control of the signalman, through the second electric bell or other alarm and a brush or brushes connected to such second bell or alarm. With such an arrangement however two sets of bells or other alarms are necessary, and the danger alarm is only sounded whilst the engine is passing over the first bar and therefore may be overlooked or forgotten. It has also been proposed to provide on the engine one audible and several visual signals for indicating "danger" or "line clear" when approaching a line signal, the operation of such audible and visual signals being effected by the closing of different electric circuits by two brushes on the engine moving in contact with two sets of movable-contact bars or rails arranged on the track and adapted to be operated by the signalman and to be connected by him to a battery in the signal cabin, the electric circuits being completed through insulated portions of the track rails over which the engine runs, but the arrangement is very complicated and necessitates the use of many moving parts.

Now an object of the present invention is to simplify and cheapen the construction and insure reliable and safe working of signaling apparatus for the purpose set forth and at the same time avoid any necessity for insulating portions of the track rails. For this purpose there are provided on the engine or other vehicle (hereinafter referred to as the engine) a visual signal, an audible signal, and electro magnetic apparatus for controlling the two signals, and on the track, in the neighborhood of and behind each line signal or signaling point which it is desired to indicate to the engine driver, are arranged separate longitudinal metallic bars one of which is independent of the line signal or signalman and the other or another of which, that is nearer to the signaling point than the first one, is under the control of the line signal and signalman, the arrangement being such that upon the engine approaching the signaling point, both the visual and audible signals will, by reason of the presence of the first bar be first operated so as to indicate danger and call the attention of the driver to the fact that he is approaching a signaling point and will continue to give such indication after the engine has passed over the said bar and also when it is passing over the second bar if the line is blocked, so as to necessitate the engine being brought to rest, whereas should the line signaling apparatus have been operated by the signalman to indicate line clear, either before the train passes over the first bar or before it passes over the second bar, this latter bar will, upon the engine running over it, cause the visual signal to be automatically returned to its normal or line clear position and the audible signal to cease sounding, thus indicating to the driver that the line is clear so that he may continue to advance.

In the accompanying illustrative drawings, Figures 1 to 5 inclusive show, diagrammatically, various arrangements of railway signaling apparatus of the kind just referred to.

According to the arrangement shown in Fig. 1, there are provided on the engine, a visual signal 1, preferably, as shown, in the form of a small semaphore pivoted to a post 2 and representing a line signal to a small size, two electro-magnetic devices 3 and 4 for operating and controlling the said visual signal, an audible signal, such as an electric bell 5, and two contact brushes 6 and 7, and upon the track and in the neighborhood of each line signal to be indicated, say a distant signal 8, are fixed two metallic bars 9 and 10 of suitable lengths, that are arranged at a distance apart, say for example one hundred yards, and one of which, viz. 9, is arranged at a distance from the corresponding line signal 8, in the direction from which trains approach such line signal, while the other, viz. 10, is arranged close to such signal. Also, there are two electric batteries 11 and 12 arranged on the engine. Bar 9 is or may be insulated. Bar 10 is insulated and electrically connected to a switch (hereinafter called for distinction the line switch), comprising for example two contacts 13 and 14, carried for example on the post of the line signal 8 and worked with such signal, either directly, as through an arm 14^X projecting from the semaphore signal 8, or through the mechanism used for operating the line signal, in such manner that when the line signal is in the "danger" position shown, the switch contacts 13 and 14 will be in the open position so that bar 10 will be insulated, and when the line signal is in the "line clear" position, the switch contacts 13 and 14 will be connected together, as by the arm 14 pressing the switch con-

tact 14 against 13, so that bar 10 will be connected to one of the "running" or track rails 15 (hereinafter for distinction called "earth"), as by the conductors 14.

Battery 11 forms part of a normally open circuit connected, as by conductors 16, 16^a to the two brushes 6 and 7 and including the electro-magnetic device 3 (hereinafter called for distinction the main magnet). Battery 12 forms part of a second normally open circuit that is connected at one end, as by conductors 17, 17^a 10 to the brush 7, and at the other end to earth, as through the engine frame and wheels, and includes the other electro-magnetic device 4 (hereinafter called for distinction the releasing magnet).

With the arrangement described, upon the engine 15 running over bar 9, the brushes 6 and 7 will bear against such bar and complete the circuit of battery 11 through the main magnet 3 and cause the armature 18 thereof to raise the visual signal 1 into the "danger" position. The terminals of the electric bell 5 are connected, as by 20 conductors 19 and 20, in shunt or parallel with the terminals of the main magnet 3 so that the current set up by contact of the two brushes 6 and 7 with bar 9, will divide at the junction of one of the bell terminals with one of the main magnet terminals, viz. 21, part passing 25 through the coils of the main magnet 3 and part through the coils of the bell 5, the two currents re-uniting at the terminal 22 after having passed through the respective coils. Therefore, the bell 5 will continue to ring as long as battery 11 continues to supply current to the 30 coils of the main magnet 3. The raising of the armature 18 of the main magnet, besides causing the visual signal 1 to indicate "danger", also closes, as through a push rod 23, a small switch, comprising for example spring contacts 24 and 25 (hereinafter called the supplementary switch 24-25), the effect of which is to complete a supplementary circuit through the contacts 24 and 25 and a conductor 26 from the conductor 20 back to the negative pole of battery 11 and thus maintain a flow of current from battery 11 through the coils of the 40 main magnet 3 and the coils of the bell 5, after the contact brushes 6 and 7 have passed completely over and left bar 9. The visual signal 1 is therefore capable of being maintained in the "danger" position for any desired length of time, and the bell will continue to ring 45 during the whole of that time. The circuit of battery 11 is completed through a second supplementary switch comprising for example two spring contacts 27 and 28 (hereinafter called supplementary switch 27-28) that is under the control of the releasing magnet 4, as through 50 the armature 29 of that magnet and a push rod 30. Upon the engine running over the second bar 10, the brushes 6 and 7 will bear against such bar, and again close the circuit of battery 11. If at the time the engine passes over bar 10 the line signal 8 is in the "danger" position, no change will be made in the position assumed by the visual signal when passing over bar 9, and the bell 5 will continue to ring. If however at the 55 time the engine passes over bar 10 the line signal 8 is in the "line clear" position, the said bar will have been earthed by the closing of the line switch 13-14, due to the movement of the signal into the line clear position, and the circuit of battery 12, will be completed through the releasing magnet 4, the brush 7, bar 10, switch 13-14, the track rails 15 and the wheels and 60 frame of the engine.

The armature 29 of the releasing magnet 4 will thereby be caused, through its rod 30, to raise switch contact 27 from the switch contact 28 and thus open the normally closed supplementary switch 27-28, which just previously formed part of the circuit of the main magnet 3 and bell 5, and thereby open the circuit of this main magnet and bell and cause the visual signal 1 to return to its normal position—the "line clear" position—and the bell 5 to cease ringing. When the brushes 6 and 7 have passed completely over the bar 75 10, the armature 29 of the releasing magnet 4 will return to its normal position and the supplementary switch 27-28 will be again closed. All the parts of the apparatus will then be in their original positions in readiness for another cycle of operations.

Means, such as a hand operated switch 31, are provided whereby the engine driver can open the circuit of the main magnet 3 and bell 5 by hand when he has obtained sufficient indication that a line signal has been passed in the "danger" position, it being understood that the signal passed is a "distant" signal which the regulations allow the driver to pass when in the "danger" position.

Fig. 2 is a similar view to Fig. 1, showing a modified arrangement of apparatus of the kind hereinbefore described. In this arrangement, one terminal of the releasing magnet 4 is connected to brush 7, and the other terminal to the engine frame. A second battery 12 is placed at each line signal 8 to be indicated such battery being placed say in a box on the signal post, and 90 has one terminal connected to earth 15 and the other to the contact 13 of the line switch 13-14 the other contact 14 of which is connected to bar 10. The arrangement is such that when the line signal 8 is in the "danger" position, bar 10 will be insulated and will 95 have no effect upon the position taken up by the visual signal 1, or upon the ringing of the bell 5 when the engine with brushes 6 and 7 passes over it, in consequence of the previous connection established between the brushes 6 and 7 by their passage over bar 9. When 100 however the line signal 8 is moved into the "line clear" position and the line switch 13-14 closed, one pole of battery 12 will be placed in connection with bar 10 whilst the other pole will be earthed on the track rails 15, and on the passage of the engine over 110 bar 10, the circuit of battery 12 will be completed through the said bar, brush 7, the releasing magnet 4 and the engine frame, and the visual signal 1 will, as before, be returned to its normal position, and the bell 5 will cease to ring. In this arrangement bar 9 need 115 not be insulated.

The modified arrangement shown in Fig. 2 will usually be the preferred arrangement, because, should the bar 10 become accidentally earthed at any time when the line signal 8 is in the "danger" position and the 120 battery 12 is carried on the engine, as in Fig. 1, a false or erroneous indication would be given by the visual signal 1 and bell 5, whereas if battery 12 be placed near and connected to the line switch 13-14 substantially as described for the modified arrangement shown 125 in Fig. 2, no danger of a false indication being given, under the circumstances mentioned, will arise.

Other modifications of the apparatus may be made to suit different conditions of service. Thus, by a modified arrangement of the brushes and bars, the re- 130

leasing magnet may be dispensed with, the return of the visual signal and the stoppage of the audible signal being effected by short circuiting the terminals of the main magnet. Fig. 3 shows, diagrammatically, 5 one arrangement of this kind, wherein the terminal 21 of the main magnet 3 and the terminal 5^a of the bell 5 are connected on the vehicle to one pole of a source of electric energy, say an electric lead 11^a, and to a contact brush 6^a, the other terminals 22 and 5^b of the said 10 main magnet and bell being connected to two other brushes 6, 6^b and also to a conductor 20 that is adapted to be placed, as by a supplementary switch 24—25, when closed by the armature 18 of the main magnet 3, in connection with the metal frame of the engine 15 and thus with earth. Bar 9 is connected to one of the track rails 15 and thus to earth. Instead of a single bar 10, as in Figs. 1 and 2, there are two parallel bars 10—10^a which are respectively connected to a pair of normally disconnected contacts 13—14 in a line switch 20 having a movable member 14^X that is adapted to electrically connect the two contacts 13—14 together only when the line signal 8 is moved into the "off" or "line clear" position. The line switch may also be provided, as shown, with two additional contacts 32 and 25 33 that are normally connected together by the movable member 14^X of the line switch when the line signal is in the "on" or "danger" position, but acts to disconnect them when the line signal is moved into the "line clear" position. One of the additional contacts, viz. 32, is connected to earth, as through the adjacent rail 15, and the other, viz. 33, to one, or preferably, as shown, to two longitudinal bars 34 and 35 arranged on the track and over and in contact with one or other of which another brush 36 carried by the 30 engine can travel. Upon the engine is also mounted a second audible signal 37, different in sound from the bell 5, for example a whistle, adapted to be placed in connection with a Westinghouse brake pipe 38, or a vacuum brake pipe 39, by a cock 40 that is under the 35 control of another electro-magnet 41. For this purpose, the cock 40 may have fixed to it a lever arm 41 that is connected to a spring 42 that tends to turn it downward but is normally prevented from doing so by a pivoted lever arm 43 that is normally held in the operative position by a spring 44 but is arranged to be moved by magnet 41, when the same is energized, into a position to release the lever 41 and allow the same to be moved by its spring 42 into a position to open the cock 40 and sound the whistle 37. One terminal of magnet 41 is 40 connected on the engine, as by a conductor 45, to one pole of the source of electric energy, for example the lead 11^a, and the other is adapted to be connected, as by a conductor 45^a, to earth through brush 36, one or other of the bars 34 and 35, and the additional contacts 45 32 and 33 of the line switch, when the line signal 8 is in the "danger" attitude. The circuit of magnet 41 may be provided with a hand switch 46 whereby, after being closed, it can be opened by hand. Contact brushes 6, 6^a, 6^b and 36, which are carried by the engine, are 45 spaced apart transversely of the track. The arrangement is such that when the engine runs over bar 9, brush 6 will complete the circuit of the main magnet 3 and bell 5 across the source of electric energy, viz. the electric lead 11^a and earth to which the opposite pole 50 of the source of electric energy is connected, and cause the visual signal 1 to move into the danger position and the bell 5 to ring, the armature 18 of the main magnet 3 at the same time moving into a position to close the supplementary switch 24, 25 so as to close the second circuit of the main magnet and bell through the conductor 20 to earth and maintain the visual signal 1 in the danger attitude and keep the bell 5 ringing after brush 6 has left bar 9. Upon the engine running over contact bars 10 and 10^a, brushes 6^a and 6^b will bear upon them and if the line signal 8 has been moved into the safety attitude, the two bars will be electrically connected through the line switch 13—14 and the brushes 6^a and 6^b will short circuit the main magnet 3 and bell 5 and so cause the visual signal 1 on the engine to return to its safety position and the said bell to cease ringing. 55 Also, brush 36 will pass idly over bar 34 or 35, as the circuit between them and earth is then open owing to the contacts 32 and 33 of the line switch being apart. If, on the other hand, the line signal be at "danger" brushes 6^a and 6^b will not short circuit the main magnet 3 and bell 5 upon passing over bars 10 and 10^a, because the circuit between these bars will be open between the contacts 13 and 14 while that between bars 34 and 35 and earth will be closed between the contacts 32 and 33 of the line switch, so that upon brush 36 coming into contact with the rail 34 or 35, according as the engine is running forward or backward, it will close the circuit of magnet 41 and enable the whistle 37 to be sounded to give an indication that the line signal 8 is at "danger". This arrangement is specially suitable for use in connection with electrically propelled vehicles, the current for the magnets 3 and 41 and bell 5 being taken, as through suitable resistance devices 37^X, from one pole 11^a of the source of electric supply used for propulsion, separate electric batteries being dispensed with. In 60 this case the magnets 3 and 41 and bell 5 on the vehicle may be duplicated and placed at the respective ends of the vehicle and used with one set of contact brushes 6, 6^a, 6^b and 36 so as to be available at either end of the vehicle. 65

According to another modification, the apparatus is adapted to enable the driver to distinguish between a line signal, such as a "distant" signal, at which he need not stop when it is in the "danger" position, and a line signal, such as a "home" signal, which he must not pass when it is in the "danger" position. For this purpose the engine may be provided with another visual signal, say in the form of a semaphore arm, that is adapted in conjunction with the audible signal, to be operated or controlled by a duplicate arrangement of apparatus of the kind hereinbefore described adapted to be brought into action by a suitable arrangement of supplementary bars and contact brushes. 70

Fig. 4 shows, diagrammatically, an arrangement as and for the purpose just described. In this arrangement, in addition to the main magnet 3, the releasing magnet 4, brushes 6 and 7, bars 9 and 10, and connections, there are provided on the engine a second main magnet 3^a for operating a second visual or semaphore signal 1^a corresponding to the home signal 8^a, a second releasing magnet 4^a for controlling the second main magnet 3^a, a second pair of brushes 7^a, 7^b, and additional supplementary switches and connections, and on the track there is or are provided between the bar 10 and the home signal 8^a, one or more intermediate insu- 75 80 85 90 95 100 105 110 115 120 125 130

lated bars, or pairs of bars 48, (two pairs are shown) each of which is arranged to make contact with one or other of the contacts 7^a or 7^b and to be connected to earth through another battery 12^a by a second line switch 5 13^a—14^a when the home signal 8^a is moved into the "off" position.

As will be seen the arrangement is such that when the engine runs over bar 9, the brushes 6 and 7 will complete the circuit of battery 11, through the coils of the 10 main magnets 3 and 3^a and bell 5, which are connected in parallel, the current passing (a) from one pole of the battery 11 through main magnet 3, supplementary switch 27 28 and connecting conductors 16 to brush 6, then through the bar 9 to brush 7, and back through the 15 conductor 16^a to the other pole of the battery, and (b) through conductor 49 and the second main magnet 3^a, and the conductor 50 and bell 5 to the point 51 and thence through the normally closed supplementary switch 27^a—28^a of the releasing magnet 4^a, conductor 20 52, and the supplementary switch 27 and 28 of the releasing magnet 4 and part of the conductor 16 to the brush 6, whence it passes through bar 9, brush 7 and conductor 16^a back to the second pole of the battery 11. The two semaphore signals 1, 1^a will consequently be 25 moved into the danger attitude by the two armatures 18, 18^a of the two main magnets 3, 3^a and the bell 5 will be caused to ring so as to give visible and audible indications that the engine is approaching the distant signaling point. The raising of the armature 18 of the 30 main magnet 3 closes the supplementary switch 24, 25, so as to complete the circuit of the battery 11 independently of the brushes, as before, and maintain the visual distant signal 1 in its operative condition after brushes 6 and 7 have left bar 9. The raising of the 35 armature 18^a of the main magnet 3^a, closes the supplementary switch 24^a, 25^a and, through conductors 54 and a switch-contact 53 that bears against the supplementary switch contact 27, maintains the visual home signal 1^a and the audible signal 5 in their operative conditions after brushes 6 and 7 have left the bar 9.

If the distant signal 8 be in the "line clear" position, then, upon the brushes 6 and 7 running over bar 10, the circuit of battery 12 will be completed, as before, through earth, the engine frame, the winding of the releasing magnet 4, part of conductor 16, brush 6, bar 10 and line switch 13—14, so that the circuit of battery 11 will be broken by the opening of the supplementary switch 27, 28 and 53 by the armature 29 of the releasing magnet 4. The signals 1, 1^a will consequently be allowed to fall into the "off" or line clear position and the bell 5 will stop ringing. If the distant signal 8 be in the "danger" position, the circuit of the battery 11 will be again closed between the brushes 6 and 7 when these move over bar 10, and the signals 1, 1^a will remain in the "danger" position and the bell 5 remaining in action. 55 If the home signal 8^a be lowered by the signalman during the time the engine is running from the distant signal 8 to the home signal 8^a, the circuit of the releasing magnet 4^a will be closed by reason of one or other of the brushes 7^a or 7^b coming into contact with one or other 60 of the bars 48, the circuit of the battery 12^a and releasing

magnet 4^a being closed through the engine frame, conductor 55, one or other of the brushes 7^a, 7^b, one or other of the bars 48 and line switch 13^a—14^a. The armature 29^a of releasing magnet 4^a will consequently rise and, through its rod 30^a, open the supplementary switch 27^a 28^a and break the circuit of battery 11, through the windings of the main magnet 3^a and bell 5 so as to allow the signal 1^a to fall into the "line clear" position and stop the bell ringing. If the engine has been brought to rest at the home signal 8^a by reason of that signal being at danger, the home indicator signal 1^a may be lowered and the bell 5 put out of action by opening a hand switch 31^a in the circuit of the main magnet 3^a and bell 5. The engine is then under the control of the home line signal 8^a.

By introducing polarized indicating devices in the circuits and arranging the contact brushes, bars, and circuits in a suitable manner for the actuation of the visual and audible signals on the engine, the distinction between different line signals of the same character, but appertaining to different lines at a diverging junction can be shown on the engine. For example, at a point at which a line diverges in two directions, there would be two "distant" signals, and two "home" signals. The two signals of the same character are 90 always erected, relatively to each other, exactly as the lines diverge. Thus, the left hand "distant" signal being approached relates to the line which diverges to the left at the junction; and, the other "distant" signal relates to the line continuing straight on or diverging 95 to the right. The "home" signals are erected under a similar rule. Therefore, a small polarized indicator mounted on the engine and carrying two numbers, say 1 and 2, could, by convention, be made to indicate always, say 1, left hand line, 2 right hand line.

Fig. 5 shows, diagrammatically, an arrangement of this kind for use at a diverging junction, A being the left hand line, B the right hand line, 8, 8^b the distant signals for the left and right hand lines A and B respectively, and 8^a, 8^b the home signals for the left and right hand lines respectively. The main magnets 3, 3^a for the distant and home signals respectively, and the releasing magnets 4 and 4^a for controlling the circuits of such main magnets, are connected up and work in the manner hereinbefore described for the arrangement 110 shown in Fig. 4. In the circuits of the releasing magnets 4 and 4^a however, there are arranged polarized subsidiary indicating devices 56 and 57 respectively for use with the distant and home signals. Each of these indicating devices has a movable indicator in the 115 form, it may be, of a disk, carrying, as shown, the numbers 1 and 2 for indicating the left and right hand lines respectively and their corresponding line signals, and a front plate formed with an aperture 58 through which the number 1 or 2 can be seen, according to the 120 direction in which the disk is turned under the action of the polarized armature of the indicating device, the direction of movement depending of course upon the direction in which current is caused to pass through the corresponding releasing magnet and indicating device. 125 For reversing the direction of the current, according as the distant signal 8 or 8^b, or home signal 8^a or 8^b is lowered, there is used, in connection with each line signal, a double switch device with a single battery 12 or 12^a common to the two distant signals 8, 8^b or to the two 130

home signals 8^a, 8^b. The switch device for the distant signal 8 comprises four spring contacts 60, 61, 62 and 63, whereof 60 and 61 are connected respectively to the negative pole of battery 12 and earth, and contacts 5 62 and 63 are connected respectively to the positive pole of the battery 12 and bar 10. The contacts are insulated from each other and so arranged that when the distant signal 8^b is pulled off, contact 60 is pressed against contact 61 and contact 62 is pressed against contact 10 63 but contacts 61 and 62 are at all times insulated from each other, so that upon brush 6 bearing upon bar 10 current will flow from one pole of battery 12 to the other through the releasing magnet 4 and polarized indicating device 56 in a direction to bring the number 15 2 opposite the aperture 58 in the said indicating device. The switch device for the distant signal 8 comprises four contacts 65, 66, 67 and 68, whereof 65 and 66 are connected respectively to bar 10 and the negative pole of battery 12, and 67 and 68 are connected respectively to earth and the positive pole of battery 12. The contacts in each pair are normally insulated from each other, and the two pairs permanently insulated from each other, as in the previous case. With this arrangement of the contacts it will be seen that when 20 25 the distant signal 8 is moved into the "line clear" position, contact 65 will be pressed against contact 66 and contact 67 against contact 68 and current will be caused to flow from the battery 12 in the opposite direction through the releasing magnet 4 and indicating device 56 with the result that the number 1 will be brought 30 35 opposite the aperture 58. The switch devices for use with the home signals 8^a, 8^b, bars 48, battery 12^a, releasing magnet 4^a and polarized indicating device 57, are constructed and operate in the same way as those 35 for the distant signal, the parts of such switches being marked with similar reference figures as those of the switches for the distant signals but with the addition of the index letter *a*.

The line indicators 56 and 57 may be of any convenient construction. Each of them may conveniently consist of a weighted plate bearing the figures 1 and 2 and to which is fixed a permanent magnet 56^a or 57^a, one end of which is arranged between the two poles of an electro-magnet 56^b or 57^b so that it can move 45 towards one or other pole according to the direction of the current through the winding of the electro-magnet. Means, such as a pivoted loop or link 56^c or 57^c, is provided for holding the plate in the position in which it is automatically moved by the electro-magnet, the said 50 55 means being arranged to be moved, as by a hand-lever 56^d or 57^d, to release the plate and allow it to move into the normal and inoperative position shown.

Further desirable information may be given to the driver by other modifications of the apparatus. For 55 instance, on passing a distant signal at "danger", the driver, if unable to see the corresponding home signal, must reduce the speed of his train to such an extent as will enable him to stop, if necessary, at the home signal, on arrival there. It may, however, be unnecessary for him to stop at the home signal on arrival there, as the line may have been cleared in the interval between passing the distant signal and arrival at the home signal. In this way, much valuable time may be lost. By providing, as shown in Figs. 4 and 5, a conductive wire 70 from the signal to any selected point

of points and connecting it to additional pairs of insulated bars 48 on the track, (one such additional pair of bars is shown) the position of the "home" signal may be indicated to the driver at short intervals during his passage between the "distant" and the "home" signals 8 and 8^a, each bar 48 then acting alike for causing the return of the indicator signal 1^a on the engine to the "line clear" position and stopping the bell 5, upon the brush 7^a or 7^b coming in contact with any of such bars 48.

In the foregoing arrangements, in which contact brushes are used, such brushes may be mounted in spring holders that will insure their coming into contact with the bars on the track and which will yield in an upward direction to prevent undue pressure between the brushes and bars.

As will be obvious the details of construction of apparatus to operate in the manner set forth can be variously modified without departing from the essential features thereof.

Having now particularly described and ascertained the nature of the said invention and in what manner the same is to be performed, I declare that what I claim is:

1. In a railway signaling system, the combination with 90 a vehicle, and the track over which the same is to travel, of signaling apparatus arranged on the vehicle and adapted when brought into action to continue in action and thereby indicate danger, means arranged at one part of the track whereby said signaling apparatus will be 95 brought into action to indicate danger when the vehicle travels over such part of the track, and means under the control of a signalman whereby upon the vehicle running over another part of the track, in advance of the first mentioned part, the said signaling apparatus can be 100 put out of action and thereby indicate line clear.

2. In a railway signaling system, the combination with 105 a vehicle and the track over which the same is to travel, of electrically operated signaling apparatus arranged on the vehicle and adapted when brought into action to continue in action and thereby indicate danger, means arranged at one part of the track whereby said signaling apparatus will be brought into action to indicate danger when the vehicle travels over such part of the track, and means under the control of a signalman whereby upon 110 the vehicle running over another part of the track, in advance of the first mentioned part, the said signaling apparatus can be put out of action and thereby indicate line clear.

3. In a railway signaling system, the combination with 115 a vehicle and the track over which the same is to travel, of a signaling device on said vehicle, a normally open circuit controlling said signaling device, means arranged at one part of said track for causing the closing of said circuit and the operation of said signaling device to 120 indicate danger when the vehicle travels over such part of the track, means adapted on the closing of said circuit to cause the signaling device to still indicate danger, and separate means under the control of a signalman whereby the said circuit can be affected to bring about the return 125 of said signaling device to its normal condition to indicate line clear.

4. In a railway signaling system, the combination with 130 a vehicle and the track over which the same is to travel, of a signaling device on said vehicle, a normally open circuit controlling said signaling device, means arranged at one part of said track for temporarily closing said circuit and bringing about the operation of said signaling device upon the vehicle running over said part of the track, a supplementary circuit arranged to be closed upon 135 the closing of the main circuit and to maintain the signaling device in action after the vehicle has passed over said part of the track, and means located at a part of the track in advance of the first mentioned part thereof

- and under the control of a signalman, whereby said circuit can be rendered inoperative on said signaling device and permit the same to return to its normal position to indicate line clear.
5. In a railway signaling system, the combination with a vehicle and a track over which the same is to travel, of an electrically operated signaling device on the vehicle, means located at one part of the track for closing the circuit of said signaling device and thereby cause the same to indicate danger upon the vehicle running over said part of the track, a supplementary circuit arranged to be closed upon the bringing of said signaling device into action and to thereby maintain the same in action to indicate danger after the vehicle has run over said 15 part of the track, and means under the control of a signalman whereby said signaling device can be returned to its normal condition, to indicate line clear, upon the vehicle running over another part of the track in advance of the first mentioned part.
20. In a railway signaling system, the combination with a vehicle and the track over which the same travels, of an audible signaling device arranged on the vehicle and adapted when brought into action to continue in action and thereby indicate danger, means arranged at one part 25 of the track whereby said signaling device will be brought into action to indicate danger when the vehicle travels over such part of the track, and means under the control of a signalman whereby upon the vehicle traveling over another part of the track in advance of the first part, the said signaling device can be put out of action and thereby indicate line clear.
25. In a railway signaling system, the combination with a vehicle and a track over which the same is to travel, of an electrically operated audible signaling device on the vehicle, means located at one part of the track for closing the circuit of said signaling device and thereby cause the same to indicate danger upon the vehicle running over said part of the track; a supplementary circuit arranged to be closed upon the bringing of said signaling device into action and to thereby maintain the same in action to indicate danger after the vehicle has run over said part of the track, and means under the control of a signalman whereby said signaling device can be returned to its normal condition to indicate line clear upon the vehicle running over another part of the track in advance of the first mentioned part.
30. In a railway signaling system, the combination with a vehicle and the track over which the same is to travel, of audible and visual signaling devices located on said vehicle, means located at one part of the track for bringing said signaling devices into action and thereby cause them to indicate danger, means for maintaining said devices in action after the vehicle has passed over said part of the track, and means under the control of a signalman whereby said signaling devices can be returned to their normal condition to indicate line clear upon the vehicle passing over another part of the track in advance of the first part.
35. In a railway signaling system, the combination with a vehicle and the track over which the same is to travel, of electrically operated audible and visual signaling devices located on said vehicle, means located at one part of the track for closing the circuits of said signaling devices and thereby cause them to indicate danger, means for maintaining the circuits of said signaling devices closed after the vehicle has passed over said part of the track, and means under the control of a signalman whereby said signaling devices can be returned to their normal condition to indicate line clear upon the vehicle passing over another part of the track in advance of the first part.
40. In a railway signaling system, the combination with a vehicle and the track over which the same is to travel, of an electrically operated signaling apparatus located on said vehicle, a longitudinally arranged bar, arranged at one part of said track and adapted upon the vehicle passing over it to bring said apparatus into action to indicate danger, means adapted upon the coming into operation of said apparatus to maintain the same in action after the vehicle has passed over said bar, and a normally inoperative second bar arranged longitudinally on the track in advance of the first bar and under the control of a signalman and whereby said signaling apparatus can be put out of action to indicate line clear when the vehicle travels over it after it has been rendered operative by the signalman.
45. In a railway signaling system, the combination with a vehicle and a track over which the same is to travel, of electrically operated signaling apparatus located on said vehicle and arranged in a normally open circuit, a longitudinally arranged bar arranged at one part of said track and adapted upon the vehicle passing over it to bring about the closing of said circuit and thereby cause said apparatus to indicate danger, means adapted upon the apparatus being brought into action to complete a supplementary circuit and maintain said apparatus in action after the vehicle has passed over said bar, and a second longitudinally arranged and normally inoperative bar on the track in advance of the first one and under the control of a signalman, whereby said signaling apparatus can be put out of action to indicate line clear when the vehicle travels over it after it has been rendered operative by the action of the signalman.
50. In a railway signaling system, the combination with a vehicle and a track over which the same is to travel, of a normally open circuit on said vehicle, electrically operated signaling apparatus arranged in said circuit, a bar arranged on the track and adapted on the vehicle passing over it to close said circuit and bring said signaling apparatus into action to indicate danger, a supplementary circuit arranged to be closed on the closing of the main circuit and to maintain said apparatus in action after the vehicle has passed over said bar, an electro-magnetic device arranged on said vehicle in a normally open circuit and adapted, when energized, by the closing of its circuit, to open the circuit of said signaling apparatus and put said apparatus out of action to indicate line clear, and a second, normally inoperative, bar arranged on the track in advance of the first bar and adapted, under the control of a signalman, to bring about the closing of the circuit of such electro-magnetic device.
55. In a railway signaling system, the combination with a vehicle and a track over which the same is to travel, of a normally open circuit on said vehicle, electrically operated signaling apparatus arranged in said circuit, a bar arranged on the track and adapted on the vehicle passing over it to close said circuit and bring said signaling apparatus into action to indicate danger, a supplementary circuit arranged to be closed on the closing of the main circuit and to maintain said apparatus in action after the vehicle has passed over said bar, an electro-magnetic device arranged on said vehicle in a second normally open circuit and adapted when energized by the closing of its circuit to open the circuit of said signaling apparatus and put such apparatus out of action to indicate line clear, a second normally inoperative bar arranged on the track in advance of the first one, and means operated simultaneously with a line signal for rendering said second bar operative for closing such second circuit when the vehicle runs over it.
60. In a railway signaling system, the combination with a vehicle and the track over which the same is to travel, of electrically operated audible and visual signaling devices located on said vehicle, means located at one part of the track for closing the circuits of said signaling devices and thereby cause them to indicate danger, means for maintaining said devices closed after the vehicle has passed over said part of the track, and means under the control of a signalman whereby said signaling devices can be returned to their normal condition to indicate line clear upon the vehicle passing over another part of the track in advance of the first part.
65. In a railway signaling system, the combination with a vehicle and the track over which the same is to travel, of electrically operated signaling apparatus located on said vehicle, a longitudinally arranged bar, arranged at one part of said track and adapted upon the vehicle passing over it to bring said apparatus into action to indicate danger, means adapted upon the coming into operation of said apparatus to maintain the same in action after the vehicle has passed over said bar, and a normally inoperative second bar arranged longitudinally on the track in advance of the first bar and under the control of a signalman and whereby said signaling apparatus can be put out of action to indicate line clear when the vehicle travels over it after it has been rendered operative by the signalman.
70. In a railway signaling system, the combination with a vehicle, and a track over which the same is to travel, of electrically operated signaling apparatus located on said vehicle, a longitudinally arranged bar, arranged at one part of said track and adapted upon the vehicle passing over it to bring said apparatus into action to indicate danger, means adapted upon the coming into operation of said apparatus to maintain the same in action after the vehicle has passed over said bar, and a normally inoperative second bar arranged longitudinally on the track in advance of the first bar and under the control of a signalman and whereby said signaling apparatus can be put out of action to indicate line clear when the vehicle travels over it after it has been rendered operative by the signalman.
75. In a railway signaling system, the combination with a vehicle and the track over which the same is to travel, of audible and visual signals, electro-magnetic means for operating such signals, normally open circuited conductors leading to such electro-magnetic means, means for maintaining the circuits of such signals closed after they have been closed, current collecting devices attached to such

- conductors, and stationary bars co-acting with the current collectors and arranged in advance of each other along the track, some of which are invariable in electrical condition and act to close the circuits of said signals while others 5 are varied in accordance with actuation of the line signals and serve when energized, to open the circuits of said signals.
16. In a railway signaling system, the combination with a vehicle and the track over which the same is to travel, 10 of audible and visual signals on said vehicle, normally open circuited electromagnetic means for operating such signals, conductors leading to such electromagnetic means, stationary bars arranged one in advance of another on the track at a distant signaling point, one for first actuating 15 the signals on the vehicle for indicating danger when the vehicle passes over it, and another for restoring the signals to normal condition when a signal to indicate line clear 20 is to be given, and bars arranged on the track in advance of the aforementioned bars for use at a home signal and under the control of a signalman for restoring to normal condition such of the signals on the vehicle as correspond thereto and have not previously been restored to normal condition.
17. In a railway signaling system, the combination with 25 a vehicle, and the track over which the same is to travel, of audible and visual signals on said vehicle, normally open circuited electromagnetic means for operating such signals, conductors leading to such electromagnetic means, current collectors attached to said conductors, stationary 30 bars on the track at a distant signaling point for first actuating and afterwards releasing all the signals on the vehicle in accordance with signals to be given at such distant signaling point, other bars arranged on the track and in advance of the aforementioned bars for use in conjunction 35 with a home signal for releasing the audible and visible signal on the vehicle corresponding thereto, and electromagnetic means on the engine, for indicating which of the distant and home signals the vehicle signals correspond to.
18. In a railway signaling system, the combination with 40 a vehicle and the track over which the same is to travel, of audible and visual signals on said vehicle, a normally incomplete electric circuit therefor, electro-magnetic devices for controlling the actuation and release of said signals, a bar arranged on the track at a distant signaling point and adapted to complete the circuit of the electro-magnetic device for bringing the signals into operation to indicate danger when the vehicle passes over it, means on the vehicle for then maintaining said circuit closed, a second bar 45 in advance of the first one for completing the circuit of the electro-magnetic device for causing said signals to resume their normal or line clear condition, a circuit for connecting the second bar with a source of electric supply, electro-magnetic indicating means adapted to be energized when the circuit of the second bar is completed, and 50 switch mechanism under the control of a signalman for changing the connection of said second bar for alternatively reversing the direction of flow of current through the indicating means when the vehicle passes over said second bar.
19. In a railway signaling system, the combination with 55 a vehicle and the track over which the same is to travel, of audible and visual signals on said vehicle, a normally incomplete electric circuit therefor, electro-magnetic devices for controlling the actuation and release of said signals, a bar arranged on the track at a distant signaling point and adapted to complete the circuit of the electro-magnetic device for bringing the signals into operation to indicate danger when the vehicle passes over it, means on the vehicle for then maintaining said circuit closed, a second bar in advance of the first one for completing the circuit of 60 the electro-magnetic device for causing said signals to resume their normal or line clear condition, a circuit for connecting the second bar with a source of electric supply, electro-magnetic indicating means adapted to be energized when the circuit of the second bar is completed, switch 65 mechanism under the control of the signalman for connection with said second bar for reversing the direction of flow of current through the indicating means, twin home signals, and means acting in accordance with the condition of either of the home signals for controlling the indication 70 of the vehicle signals corresponding thereto.
20. In a railway signaling system, the combination with a vehicle and the track over which the same is to travel, of audible and visual signals on said vehicle, a normally incomplete electric circuit therefor, electro-magnetic devices for controlling the actuation and release of said signals, a bar arranged on the track at a distant signaling point and adapted to complete the circuit of the electro-magnetic device for bringing the signals into operation to indicate danger when the vehicle passes over it, means on the vehicle for then maintaining said circuit closed, a second bar in advance of the first one for completing the circuit of the electro-magnetic device for causing said signals to resume their normal or line clear condition, a circuit for connecting the second bar with a source of electric supply, electro-magnetic indicating means adapted to be energized when the circuit of the second bar is completed, twin distant signals, switch mechanism operated by either of the twin distant signals alternatively for reversing the direction of current flow through the indicating means, twin home signals, a track bar in conjunction with such home signals, a circuit connecting such bar with a source of electric supply, electro-magnetic indicating means adapted to be energized when the circuit of the last mentioned bar is completed, and switch mechanism operated by either of the home signals alternatively for reversing the direction of flow of current through the indicating means of such home signals.
21. In a railway electrical signaling system, the combination with a vehicle and the track and line signals therefor, of a normally open main circuit, an electric bell and electro-magnet therein, a visual signal arranged to be moved into the danger attitude by the armature of said magnet when the latter is energized by the closing of said circuit, contacts connected to the terminals of said circuit, a normally open supplementary circuit for said bell and magnet, a supplementary switch arranged to be operated by said armature to close said supplementary circuit when said magnet is energized, said parts being on said vehicle, bars arranged on the track one in advance of the other at a distant signaling point, one of said bars being adapted to temporarily close the main circuit through said contacts when the vehicle passes over it, and a line switch arranged to be operated when a line signal is actuated to indicate line clear and thereby cause another of said bars to bring about the opening of the supplementary circuit and the consequent return of the bell and visual signal to the line clear condition.
22. In a railway signaling system, the combination with a vehicle and the track and line signals therefor, of a normally open main circuit, an electric bell and main magnet therein, a visual signal arranged to be moved into the danger attitude by said magnet when the same is energized by the closing of said circuit, contacts connected to the terminals of said circuit, a normally open supplementary circuit for said bell and main magnet, a normally open 110 supplementary switch arranged to be operated by said magnet, when energized, to close said supplementary circuit, a releasing magnet in third normally open circuit, and a second, normally closed, supplementary switch arranged to be operated by said releasing magnet when energized, to open said supplementary circuit, said parts being on the vehicle, a bar arranged on said track at a distant signaling point and adapted to temporarily close the main circuit through said contacts when the vehicle passes over it, a second bar arranged on the track in the neighborhood of the distant signaling point and in advance of the first bar, and a line switch arranged to be operated when a line signal is actuated to indicate line clear and thereby to enable said second bar to close the circuit of said release magnet when the vehicle passes over it.
23. In a railway signaling system, the combination with a vehicle and the track and line signals therefor, of a normally open main circuit, an electric bell and main magnet therein, a visual signal arranged to be moved into the danger attitude by said magnet when the same is energized by the closing of said circuit, contacts connected to the terminals of said circuit, a normally open supplementary circuit for said bell and main magnet, a normally open supplementary switch arranged to be operated by said magnet, when energized, to close said supplementary circuit, a 130

- two line switches arranged to be operated when the respective distant line signaling apparatus is operated to indicate line clear for one or other of the two branch lines at the junction, one of said line switches when closed 5 by the operation of its corresponding distant line signaling apparatus for indicating line clear for one branch line being arranged to connect one pole of said stationary generator to earth and the other to said insulated bar, and the second line switch when closed by the operation of its 10 corresponding distant-line signaling apparatus for indicating line clear for the other branch line being arranged to reverse the connection of the poles of the said generator to the insulated bar and earth, and a route indicator arranged to be moved in one direction when current is caused 15 to flow in one direction through the distant releasing magnet after one line signaling apparatus has been operated to indicate line clear for one branch line or route, and in the opposite direction when current is caused to flow in the contrary direction through said distant releasing magnet after the other line signaling apparatus 20 has been operated to indicate line clear for the second branch line or route.
28. In a railway signaling system, the combination with a vehicle, a track having a junction with two branch lines 25 therefor, and home and distant line signaling mechanism for said branch lines, of electric signaling and controlling apparatus arranged on said vehicle and comprising an electric generator, an electric bell and distant and home main magnets in the main circuit of said generator and in parallel with each other, separate distant and home visual signals arranged to be moved into the danger attitude by said magnets when energized by the closing of the main circuit of said generator, two separate normally open supplementary circuits for said magnets and bell, two separate 30 normally open supplementary switches arranged to be operated by the respective main magnets to separately close the two supplementary circuits when the main circuit is closed, two normally closed switches arranged in the said supplementary circuits and one of which when opened, 35 opens the circuit of both main magnets and the bell and the other of which when opened opens the circuits of the home main magnet and bell, and distant and home releasing magnets each having one terminal connected to earth and the other to an insulated contact and adapted when energized to open the corresponding normally closed supplementary switch and supplementary circuit, two bars arranged on the track in the neighborhood of the distant signaling point, one of said bars being arranged to short circuit the contacts connected to the main circuit and the other being insulated and arranged in advance of the first one and so as to make connection with the contact connected to one terminal of the distant releasing magnet, a stationary electric generator having one pole connected to earth, two line switches arranged at the distant signaling 40 point, one of said line switches being arranged to be closed when the distant line signal for one branch line is operated to indicate line clear and to then connect one pole of the stationary generator to earth and the other to said insulated bar, and the other line switch being arranged to be closed when the other distant line signal for the second branch line is operated to indicate line clear and to then reverse the connection of said stationary electric generator to earth and said insulated bar, a route indicator arranged to be moved in one direction when the current is caused to flow in one direction through the said distant 45 releasing magnet for one route and in the opposite direction when current is caused to flow in the reverse direction through said releasing magnet, a second insulated bar arranged behind and near to the two sets of home line signaling apparatus for the two branch lines and to make connection with the contact connected to one terminal of the home releasing magnet, a stationary battery, two line switches under the control of the two sets of home line signaling apparatus and arranged to connect said second insulated bar to one or other pole of said stationary generator and the opposite pole to earth, and a second route indicator arranged to be moved in one direction when current is caused to flow in one direction through the home releasing magnet and in the opposite direction when current is caused to flow in the reverse direction through said 50 magnet.
29. In a railway signaling system, the combination with a vehicle, and a track over which the same is to travel, of electrically operated signaling apparatus located on said vehicle and arranged in a normally open circuit, a longitudinally arranged bar arranged at one part of said track and adapted upon the vehicle passing over it to bring about the closing of said circuit and thereby cause said apparatus to indicate danger, means adapted upon the apparatus being brought into action to complete a supplementary circuit and maintain said apparatus in action after the vehicle has passed over said bar, a second longitudinally arranged and normally inoperative bar on the track in advance of the first one and under the control of a signalman, whereby said signaling apparatus can be put out of action to indicate line clear when the vehicle travels over it after it has been rendered operative by the action of the signalman and one or more additional longitudinally arranged and normally inoperative bars arranged on the track in advance of the second bar and under the control of the signalman and adapted to act like the second bar.

Signed at Newcastle-on-Tyne, England, this ninth day of April, 1907.

VINCENT LITCHFIELD RAVEN.
